CLAIM

The ornamental design for a combination storage container and interlocking disc for recordings, as shown and described.

DESCRIPTION

FIG. 1 is an exploded perspective view of a combination storage container and interlocking disc for recordings showing my new design, the side of the interlocking disc which is not shown being a mirror image of the visible side;

FIG. 2 is a right side elevational view thereof, the left side being a mirror image;

FIG. 3 is a top plan view thereof, the bottom plan view being a mirror image;

FIG. 4 is a rear elevational view thereof; and,

FIG. 5 is a front elevational view thereof.

FIG. 1***FIG. 2***

FIG. 3

FIG. 4

FIG. 5
